ANKLE JOINT FOR ARTIFICIAL LIMBS

Noel F. Harrington, Los Angeles, Calif.

Application June 14, 1943, Serial No. 490,716

5 Claims. (Cl. 3-7)

My invention relates to artificial limbs and has particular reference to an ankle joint for use with an artificial leg and foot to reproduce both in shape and action the effect of a normal ankle joint.

In the construction and operation of artificial legs considerable difficulty has been encountered in providing an ankle joint which will provide both the universal pivot action of a normal ankle joint and at the same time provide for the absorption of shocks and to reproduce artificially a replica of muscular action of the normal muscles of the foot, ankle and leg in walking or other movements to be given to the artificial leg.

Previous types of ankle joints have consisted either of a single pivotal action in which the pivot extends transverse to the rest of the foot to provide a forward and rearward rocking motion between the leg and foot in a walking motion, while other types of legs have attempted to provide a limited amount of sidewise pivotal motion to aid in the adaptation of the foot to uneven surfaces upon which the foot may be required to impinge or to rest, this latter motion being provided in an effort to avoid the twisting strains which would be placed upon the artificial leg where one or the other side of the foot would engage an upwardly extending projection such as a stone or uneven ground surface which would normally be encountered in a walking motion.

These previous devices, however, have not proved satisfactory largely for the reason that the pivotal joints are formed between metal parts which places substantial weights or masses at the end of the leg, lending a considerable amount of inertia to the pendulum action of the leg as it swings from front to back and making it difficult for the wearer to control the movement of the leg and producing a noticeable lack of reality in the forward movement of the leg when walking.

Another defect in the previous constructions is that even though sidewise pivotal motion is given to the foot, the movement is not progressively retarded as would be accomplished by the natural muscular action of the normal ankle, with the result that the sidewise motion renders the leg and foot rather unstable and difficult for the wearer to control.

It is, therefore, an object of my invention to provide an ankle joint for artificial legs in which a minimum of mass is provided in the ankle joint to thus reduce the moment of inertia in the pendulum action of the leg.

Another object of my invention is to provide an ankle joint in which the joint between the

leg and the foot is made through an elastic medium which will provide a universal pivotal action of the foot relative to the leg.

It is a still further object of my invention to provide an ankle joint of the character set forth in the preceding paragraph wherein the elastic medium is so arranged as to be readily yieldable in the initial pivotal movement but which will provide progressively increasing resistance to increase of the movement in a manner substantially duplicating the muscular action in a normal ankle joint.

Another object of my invention is to provide an ankle joint of the character described in which the leg and foot are connected near the rear of the foot by an elastic medium which will yield under compression at the instant of impact of the heel with the ground surface and then will provide an elastic tension between the leg and the heel as the leg pivots forward while the foot is still upon the ground, thus providing a replica of the tension produced by normal ankle muscles as the normal leg and foot are rocked forwardly in the walking action.

Other objects and advantages of my invention will be apparent from a study of the following specifications, read in connection with the accompanying drawing, wherein:

Fig. 1 is an elevational view partly in section of an artificial leg and foot provided with the ankle joint of my invention;

Fig. 2 is a vertical sectional view of the leg, foot and joint illustrated in Fig. 1, a section being taken along the line II-II of Fig. 1;

Fig. 3 is an elevational view partly in section of the leg, foot and joint shown in Fig. 1 and illustrating the position of the parts at the instant of impact of the heel with the ground surface in making a walking step; and

Fig. 4 is an elevational view partly in section of the foot, leg and ankle in the next progressive portion of the walking movement.

Referring to the drawing, I have illustrated in Fig. 1 an artificial leg and foot comprising a leg member 1 which may be formed of any suitable material and of any desired shape, preferably hollow for the purpose of reducing the weight. The leg member 1 terminates at its lower end in an end wall 2 to which is secured a metal plate 3 as by means of a stud 4 and a nut 5.

The foot member 6 may be constructed of any suitable material and given any desired shape so long as it is provided with a substantially flat upper surface 7 to which may be secured a second metal plate or foot plate 8 as by means of

a stud 9 and a nut 10, the under surface of the foot being preferably counterbored as indicated at 11 to provide a recess for the reception of the end of the stud 9 and the nut 10.

Interposed between the leg plate 3 and the foot plate 8 are two supporting posts 12 and 13, the post 12 being disposed toward the front portion of the foot and leg while the rear post 13 is disposed rearwardly of the leg and foot so that pressure loads between the leg and foot will be distributed over a considerable portion of the front to rear areas of the plates 3 and 8.

The front post 12 is preferably constructed of natural or synthetic rubber having considerable resiliency, both under compression and under tension, and to aid in the provision for a substantially universal pivotal action between the foot 6 and the leg 11 I prefer to form the post 12 about a core 14 of rubber or similar material having fabric or similar reinforcing material included therein to render the core less yielding than the surrounding material of the post 12. The shape of the core 14 may be that of a sphere, though I prefer that it be circular in front to rear cross section and oval or elliptical in left to right cross section as is illustrated in Figs. 1 and 2. This shape provides for a short radius front to rear pivoting action between the foot and leg and provides also a substantially long radius sidewise pivotal action to permit the foot to be self-adjusting for uneven ground surfaces and thus reproducing the normal sidewise pivotal motion of a normal ankle joint.

With the construction of the post 12 and its core 14 as described, it will be apparent that during the normal walking motion the impacts of the foot against the ground will be cushioned by the resiliency of the post 12, the post 12 tending to compress by gradually and progressively building up resistance to the compression as the downward pressure increases between the leg and foot, while at the same time the foot will yield sidewise to conform to lateral unevenness of the ground upon which the foot impinges with an action permitting ready initial yield and a gradually increasing resistance to the yield as the downward pressure is exerted by the leg. Thus both the cushioning effect of the normal ankle joint in the initial impact and the normal sidewise turning or yielding with its gradual resistance to the yield of a normal ankle joint is effectively reproduced by my post 12.

The post 12 may be secured to the plates 3 and 8 in any suitable manner, though I prefer that the upper and lower surfaces of the post 12 be vulcanized directly upon the plates 3 and 8, respectively, so that no other interconnecting mechanism is needed. By using this vulcanized joint, the total weight of the ankle joint may be kept at a minimum and the material of which the plates 3 and 8 are constructed may be selected to provide a minimum of weight for these parts as, for example, by employing aluminum, manganese or other light-weight metals or plastics having sufficient strength to provide the interconnection between the foot and leg but with a minimum of weight.

Thus by dispensing with bolts and metal pivot joints, I am enabled to keep the mass at the ankle joint at a minimum and reduce the inertia effect in the pendulum action of the swinging of the leg from front to back.

The rear post 13 is likewise constructed of rubber cured to provide resiliency both in compression and in tension, the upper and lower sur-

faces of the post 13 being preferably vulcanized to the surfaces of the plates 3 and 8, respectively, the post 13 preferably having a greater vertical dimension than the post 12 to provide for a greater amount of motion between the rear portion of the foot and leg than is permitted at the forward portions of these members. Thus, as is illustrated in Fig. 3, at the instant of impact of the heel upon the ground and the subsequent application of the weight of the wearer to the foot, the rear post 13 will be substantially compressed, absorbing the shock and permitting the foot and leg to yield relative to each other as the foot rocks forwardly upon the heel to place the ball of the foot into contact with the ground surface. This action is a duplication of the action of a normal ankle joint during this initial part of a walking step.

Also during this phase of the walking action, as is shown in Fig. 3, the forward portion of the forward post 12 will be under tension yieldingly resisting downward movement of the ball part of the foot, easing that motion in the same manner as the muscles of the normal ankle would lower the ball of the foot into contact with the ground surface.

Then as the leg portion swings forward above the now stationary portion of the foot the forces are reversed, the front post 12 having its forward section under compression, the core 14 acting as the pivotal axis while the rear post 13 is placed in tension by the separation of the rear sections of the plates 3 and 8 from each other. Thus the rear post produces a muscular-like action tending to lift the heel of the foot from the ground surface in substantially the same manner as the normal muscular action of an ankle joint and the heel of the foot is resiliently raised from the ground surface after the leg 4 has pivoted to a natural forward position while the entire foot has been permitted to rest in contact with the ground surface.

In order to permit a relatively great amount of stretch in the rear post 13 and yet insure the natural lifting of the heel, I prefer to provide a reinforcing fabric strip 15 adjacent the rear of the post 14, such strip being either embedded within the post 13, as illustrated, or it may be mounted upon the plates 3 and 8 externally of the post 13. This fabric strip will provide a limit to the amount of separation permitted between the rear edges of the plates 3 and 8 and will insure the positive lifting of the heel when, in the walking motion, the leg and foot have assumed the positions shown substantially in Fig. 4.

While it will be understood that the front and rear posts 12 may be made integral with each other, I prefer to form them as separate posts, providing a space 16 between them, thus reducing the amount of material in the ankle joint and minimizing the mass or weight which will be concentrated at the joint.

To finish off the joint and provide a smooth external appearance, the space between the extreme outer edges of the plates 8 and 3 may be filled with sponge rubber or other suitable yielding and preferably elastic material as indicated at 17 and 18 secured to both the upper and lower plates 3 and 8, respectively, as by suitable adhesive or directly vulcanizing the material to the plates 3 and 8.

From the foregoing it will be apparent that I have provided an ankle joint in which the weight concentrated at the ankle joint may be maintained at an extremely low value to thus provide

for a more natural appearance in use and a greater ability of the wearer to control the swinging movements of the leg and foot.

It will also be noted that a natural pivotal action both front to rear and sidewise is provided in which the pivotal action is relatively free during the initial pivotal motion but is increasingly resisted as the pivotal motion is increased. At the same time both an adequate cushioning of impacts is provided as well as a strong tension action, tending to rock the foot upon the ball portion thereof as the leg pivots forward in a natural walking motion, the net result of which is to reproduce with great fidelity the action of a normal leg, foot and ankle joint.

While I have illustrated the posts 12 and 13 as being attached to metal plates which are in turn attached to the foot and leg portions, it will be apparent that the plates may be made of plastic or any other suitable composition having the necessary strength and rigidity and also that these posts may be attached in any suitable manner directly to the foot and leg portions, thus dispensing with the plates if desired.

It will also be apparent that by forming the posts and plate assemblies as a unit, the construction of the joints may be simplified, permitting the units to be maintained in stock and assembled on foot and leg portions as desired.

While I have shown and described the preferred embodiment of my invention, I do not desire to be limited to any of the details of construction shown or described herein, except as defined in the appended claims.

I claim:

1. In an artificial leg, a leg member, a foot member, a post of resilient material interposed between the members to form a universal pivotal connection between said members, and a core of resilient material embedded in said post and having a resilience less than that of said post for limiting the movement of said members toward each other.
2. In an artificial leg, a leg member, a foot member, a post of resilient material interposed between the members to form a universal pivotal connection between said members, and a core of

less resilient material disposed between the upper and lower ends of said post for limiting the relative vertical movement of said members toward each other, and having a substantially circular cross section in a vertical plane extending lengthwise of said foot member and having an elliptical cross section in a vertical plane extending transversely of the length of said foot, whereby the outer surfaces of said core define the radii of the pivotal motion between the members.

5 3. In an artificial leg, a leg member, a foot member, a substantially non-resilient element disposed between said foot and leg members having curved upper and lower surfaces presented to said members to define a pivot about which said members may rock relative to each other, and elastic means interconnecting said members to resiliently limit the rocking movement permitted between said members.

15 4. In an artificial leg, a leg member, a foot member, a substantially non-resilient element disposed between said foot and leg members having curved upper and lower surfaces presented to said members to define a pivot about which said members may rock relative to each other, and elastic means surrounding said non-resilient element and interconnecting said foot and leg members to resiliently limit the rocking movement of said foot and leg members relative to each other.

25 5. In an artificial leg, a leg member, a foot member, means interposed between said foot and leg members to space said members apart, said means being formed of resilient rubber material vulcanized to plates respectively secured to said foot and leg members, a core in said means of substantially non-resilient material disposed adjacent the forward portion of said foot and leg members to act as a fulcrum about which said members may have a limited universal pivotal movement, and a limiting strip embedded in said means toward the rear of said foot and leg members to limit the stretch of the rear portion of said means to a predetermined spacing of the rear portion of said foot and leg members away from each other.

NOEL F. HARRINGTON.
